DESIGN FOR A BOTTLE

Charles A. Lasley, Los Angeles, Calif., assignor to Beverages of America, Inc., Los Angeles, Calif.,
a corporation of California

Application March 29, 1941, Serial No. 99,997

Term of patent 14 years

To all whom it may concern:

Be it known that I, Charles A. Lasley, a citizen of the United States, residing at 524 North Sierra Bonita Avenue, Los Angeles, in the county of Los Angeles and State of California, have invented a new, original, and ornamental Design for a Bottle, of which the following is a specification, reference being had to the accompanying drawing, forming part thereof.

Referring to the drawing:

Figure 2 is a rear elevational view of said bottle; and

Figure 3 is a developed view of the design on the bottle surface a portion being broken away for convenience of illustration.

I claim:

The ornamental design for a bottle, as shown.

CHARLES A. LASLEY.
